US00D611468S

(12) **United States Design Patent**
Yun et al.

(10) **Patent No.:** **US D611,468 S**
(45) **Date of Patent:** **** Mar. 9, 2010**

(54) **NOTEBOOK COMPUTER**

(75) Inventors: **Yeo-Wan Yun**, Seoul (KR);
Seung-Wook Jeong, Seoul (KR)

(73) Assignee: **Samsung Electronics Co., Ltd.**, Suwon,
Kyunggi-do (KR)

(**) Term: **14 Years**

(21) Appl. No.: **29/314,207**

(22) Filed: **Mar. 13, 2009**

(51) **LOC (9) Cl.** **14-02**

(52) **U.S. Cl.** **D14/315**

(58) **Field of Classification Search** **D14/315-328;**

(57) **CLAIM**

The ornamental design for a notebook computer, as shown and described.

DESCRIPTION

FIG. 1 is a top front perspective view of a notebook computer showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

1 Claim, 4 Drawing Sheets
